SPARK PLUG ATTACHMENT

Filed May 18, 1925

Inventor:
Roy C. Floyd
By Arthur A. Durand, Atty.

Patented Apr. 19, 1927.

UNITED STATES PATENT OFFICE.

ROY C. FLOYD, OF CHICAGO, ILLINOIS, ASSIGNOR TO UNIQUE SPARK PLUG CLEANER CO., OF CHICAGO, ILLINOIS, A CORPORATION OF ILLINOIS.

SPARK-PLUG ATTACHMENT.

Application filed May 18, 1925. Serial No. 30,967.

This invention relates to devices for attaching spark plugs to engines, and for cleaning spark plugs by the action of a jet of fire which is allowed to escape through 5 the attachment, and which then impinges upon the end of the plug to be cleaned.

Generally stated, the object of the invention is to provide an attachment which can be screwed into the threaded socket ordinarily occupied by the spark plug, and into 10 the outer end of which both the spark plug necessary for the operation of the engine and the holder for the spark plug to be cleaned can be inserted.

It is also an object to provide a novel 15 construction and arrangement whereby the air drawn into the cylinder, through the spark plug cleaner, will not interfere with the operation of the spark plug which is in the use on the engine and will not interfere with the ignition of the charge.

It is also an object to provide certain 20 details and features of construction and combinations tending to increase the general efficiency and the desirability of an attachment 25 of this particular character.

To the foregoing and other useful ends 30 the invention consists in matters hereinafter set forth and claimed, and shown in the accompanying drawings, in which—

Fig. 1 is a side elevation of a spark plug attachment embodying the principles of the invention, showing the same screwed into the socket ordinarily occupied by the spark plug, 35 and showing said plug instead screwed into the outer end of the attachment, and showing the spark plug cleaner also screwed into the top of the attachment at one side of the plug.

Fig. 2 is a vertical section of said attachment and spark plug cleaner, showing a spark plug screwed into the outer end of the cleaner, and showing the plug which is necessary for the operation of the engine in dotted lines.

As thus illustrated, the attachment 1, sometimes called an adapter, is formed with a relatively large threaded socket 2 to receive the spark plug 3 which is necessary for 50 the operation of the engine. The top of the attachment is also formed with a relatively small threaded socket 4 into which the threaded end portion 5 of the spark plug cleaner 6 is inserted, so that the cleaner 55 stands at an angle as shown. Said cleaner

has its upper portion provided with a threaded socket 7 to receive the plug 8 to be cleaned, and the sides of this socket have openings 9 as shown. The cleaner has a passage 10 leading from the socket 4, to 60 permit the jet of fire to escape and impinge against the edge of the spark plug 8, a suitable valve 11 being provided for controlling said passage. The lower portion of the attachment 1 is provided with a threaded boss 12 which can be screwed into the socket ordinarily occupied by the spark plug and a relatively large passage 13 which extends upwardly to permit the explosive mixture 65 to enter and be ignited by the sparking action of the spark plug 3, so that the latter will function in the ordinary manner. The attachment 1 also has a relatively small passage 14 leading upwardly to the socket 4, and it will be observed that this passage 70 75 14 extends some distance below the lower end of the passage 13, whereby the air sucked into the passage 10 and socket 4 and passage 14 does not enter close enough to the electrodes of the plug 3 to interfere with proper 80 ignition of the charge.

Thus the plug 8 is cleaned by the jet of fire produced by action of the plug 3, as when the charge is fired a jet of fire and hot gases will escape through the passage 14 85 and through the passage 10 and impinge upon the end of the plug 8, thus burning off the carbon which may have accumulated on the end of the plug. By use of the attachment 1 it is easy to install the cleaner on the engine, in a way that does not necessitate dispensing with any of the devices on the engine. One of the spark plugs of the engine is simply taken out and inserted in the socket 2, as shown, and the attachment 1 90 is then screwed into the socket that was occupied by said plug, as shown in Fig. 1, and with the valve 11 closed the engine will operate in the regular manner. When it is desired to clean a plug, the plug to be 95 cleaned is merely screwed into the upper end of the cleaner, as shown in Fig. 2, and the valve 11 is opened to permit the escape of the fire and hot gases against the end of the plug to be cleaned, in the manner explained. While the attachment is shown in use for 100 allowing the fire and hot gases to escape from the engine for the purpose of cleaning spark plugs, it is obvious that this escape 105 of gases directly from the cylinder of the 110

engine can be employed for any suitable or desired purpose.

Without disclaiming anything, and without prejudice to any novelty disclosed, what I claim as my invention is:—

1. Instrumentalities for cleaning spark plugs, comprising an internal combustion engine, means for permitting the fire and explosive pressure to escape from the engine, and means for presenting the plug to be cleaned to the impinging blast of fire which has escaped from the engine, said engine being operative to produce said cleaning blast of fire independently of the plug to be cleaned, so that the plug is cleaned while not operative to function as a spark plug, a socket piece screwed into the opening ordinarily occupied by the spark plug of the engine, forming a support for said plug presenting means, and a spark plug screwed into said socket piece to ignite the charge in the engine, said socket piece having a passage leading to the operative spark plug, and an entirely separate and smaller discharge passage leading to the plug to be cleaned.
2. A spark plug cleaner comprising a hollow body having a passage to form a jet of hot gases and fire, and having an expansion chamber to receive said jet, in which the plug to be cleaned is inserted, adapted to hold the plug such a distance from the end of said passage that the jet of gases and fire will pass through said chamber and impinge upon the end of the plug, a socket piece adapted to be screwed into the opening ordinarily occupied by the spark plug of an engine, having a passage leading to the operative spark plug, and a separate and smaller discharge passage leading to the plug to be cleaned, forming a support for said hollow body, and providing a socket for the spark plug of the engine, said chamber having an outlet communicating with the atmosphere, whereby the impinging jet

is free to expand in said chamber and finally escape into the atmosphere.

3. In a spark plug cleaner, means providing a passage to form a fluid jet of flame and gases for cleaning the plug, means for holding the plug a distance from the end of said passage and in position to have the jet violently impinge thereon, means for controlling said passage without disturbing the position of said plug, a socket piece to support all of said means, and means including an operative spark plug screwed into said socket piece, and independent of said plug to be cleaned, for producing explosive pressure to form said cleaning jet, said socket piece having one passage leading to the operative plug, and having an entirely separate and smaller discharge passage leading to the plug to be cleaned.

4. In combination with an internal combustion engine, a spark plug cleaner mounted on the engine, having means to form a passage through which hot gases and fire and flame may escape from the cylinder of the engine, and having means for holding the plug to be cleaned in position to receive the impinging blast or jet of flame, said cleaner being adapted to receive ordinary spark plugs for cleaning purposes, another spark plug combined with said cleaner to form a unit therewith, which unit as an attachment is insertable in the opening ordinarily provided on the engine for a spark plug, thereby operative to produce said jet of flame independently of the plug to be cleaned, said unit having one passage leading to the operative plug, and having an entirely separate discharge passage leading to the plug to be cleaned, and means for shutting off the discharge of flame while the cleaner is empty and not in use, and while the engine is running for ordinary purposes.

Specification signed this 15th day of May, 1925.

ROY C. FLOYD.
